The ornamental design for a combined cigar case with ashtray, as shown and described.

DESCRIPTION

FIG. 1 is a front, top perspective view of a combined cigar case with ashtray, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 2; and,

FIG. 10 is another perspective view of the combined cigar case with ashtray, shown in an alternative position.

The dashed lines in the figures illustrate portions of the combined cigar case with ashtray that form no part of the claimed design. The dash dot dash lines in FIGS. 2 and 9 are for the purpose of illustrating the enlarged view indicators and form no part of the claimed design.
